CONTAINER CLOSURE AND DISPENSING DEVICE

Edward Richard Hacmac, Hollywood, Calif., assignor to Na-Mac Products Company, a corporation of California

Application October 28, 1938, Serial No. 237,506

2 Claims. (Cl. 221—14)

Cans, bottles and the like in general use today and for many years past for packaging liquids and the like for distribution and use by the ultimate consumer, have their upper dome shaped end terminating in a centrally disposed and constricted dispensing opening or spout. Generally these containers with their contents sold and shipped commercially are provided with a screw threaded cap which screws onto the constricted dispensing opening or spout. It is difficult for the ultimate consumer to use this package as a server for pouring out a portion of the contents from time to time as the occasion requires, particularly if the contents are of a viscous nature, because on each occasion the consumer must unscrew the cap and after so doing, it is impossible to pour the contents without causing drippings, which are not only aggravating but result in waste. It is, therefore, an object of my invention to provide a simple, inexpensive self-contained combination closure, dispenser and drip cut device which can be readily attached to and detached from such constricted necks or dispensing openings in place of the original or conventional cap and when so attached will provide an efficient drip cut device.

A further object is to provide such a device consisting of few parts, namely, a body member stamped from a single piece, having a constricted portion, the upper end of the constricted portion provided with a dispensing opening and guideways for a slidable shearing member, and a spring actuated lever provided on the body member for actuating the slidable shearing member.

The above and other features, advantages and capabilities will become apparent from the following description and accompanying drawing in which I have illustrated one form of my invention but the construction there shown is to be understood to be illustrative only and not as defining the limits of my invention.

In the drawing:

Fig. 1 is a side view in elevation of a container equipped with my novel invention.

Fig. 2 is a top plan view of the same.

Fig. 3 is a vertical cross sectional view taken on the line 3—3 of Fig. 2.

Fig. 4 is a fragmentary view in horizontal cross section taken on the line 4—4 of Fig. 3, and

Fig. 5 is a perspective view of the cap portion of my device.

Referring more particularly to the embodiment disclosed in the drawing, my invention is shown in Fig. 1 as applied to a container 1 having tapered top portion 2 welded or otherwise attached

thereto and terminating in restricted, threaded neck portion 3 and having an opening therethrough for dispensing the contents of the container.

To replace the usual cap for such a container, I provide my novel device which comprises a cap portion having collar 4 of the proper size to fit over the neck of the container and in which are pressed a plurality of thread segments complementary to and adapted to receive the threads on the container neck for screwing the device onto this neck. Below the neck portion is a downwardly flared skirt portion 5 adapted to provide a base for the handle as hereinafter described.

Above the collar is reduced neck portion 6 in one side of the top of which is suitably formed an arcuate lipped pouring spout or opening 7 and inwardly turned, spaced lugs or projections 8 adapted to form a guideway and retaining means for slidable closure and drip shearing blade 9. This blade is of relatively thin and resilient metal and forms a movable or slidable shearing element which when closed tightly contacts the upper edge of the spout and coacts therewith to shear off and forcibly hurl or propel the residue or final part of the sheared flow away from the spout and thereby eliminate or prevent dripping. In order to accomplish this I make the shearing member a little wider than the spout opening and provide the blade with a curved shearing edge 10, the radius of the curve of the shearing edge being slightly greater than the radius of the arcuate front edge of the spout. On the side of the top portion opposite the spout is a vent or opening 11 to admit air to the container to insure the free and even pouring of the contents thereof.

In order to rapidly propel the blade 9 across the spout to close the same and cut the flow therefrom, the rear end of the blade is bent sharply to provide a depending portion which is inserted in a slot in the top of the combination handle and lever 12 for operating the blade 9. This handle is arcuate and of inverted U-shape in cross section, the sides thereof gradually decreasing in height toward its free end. Spanning the lower front part of the sides of the handle, through suitable openings therein is a pin 13 rotatably mounted in openings in spaced tabs or lugs 14 cut and pressed out from the skirt 6 of the cap portion. On this pin is also mounted a coil spring 15, one end of which extends under the skirt 5 through one of the openings formed by cutting and pres-

sing out the tab 14 and the other end bears against the underside of the top of lever 12.

In operation, the device is screwed onto the container in place of the original cap and the container is so grasped by the operator that he can manipulate the handle to draw the free end down and toward the side of the container and against the action of the spring, as shown in dotted lines in Fig. 3. The handle draws with it the closure and drip shearing blade 9 to open the spout and permit pouring therefrom. The spring is relatively heavy and tends at all times to move the handle forward and upward whereby to move the blade to close the spout and shear the drip therefrom. Consequently, when the handle or lever is released the spring will rapidly raise the lever to its forward, raised position whereby to rapidly propel or shoot the blade over the spout, shearing and hurling the last vestige 20 of the liquid away from the spout.

It is apparent that I have provided an effective seal or closure for a container and one which provides a spout which will pour freely and evenly without dripping. The handle is adapted to be 25 grasped for facilitating movement of the container to which my device is attached and when so used will not work against the action of the spring but will assist it in keeping the spout closed and also constitutes the lever for opening the

spout. The device consists of very few parts and can be made at a low cost.

Having disclosed the invention, I claim:

1. A closure and dispensing device for a container, comprising a cap adapted to replace the container cap and formed from a single piece of sheet metal, a collar on said cap for fitting onto the container, a neck portion above said collar and having a spout and guideway therein, means in said guideway adapted to be moved to close said spout and shear the flow therefrom, a skirt below said collar and having upstanding lugs thereon, a member mounted for oscillation on said lugs and connected to said closure, said member being adapted for use as a handle and to reciprocate said closure. 5

2. A closure and dispensing device for a container, comprising a cap adapted to replace the container cap, a collar on said cap for fitting onto the container, a neck portion above said collar and having a spout therein a guideway in the top of said neck portion, means in said guideway adapted to be moved to close said spout and shear the flow therefrom, a member mounted for oscillation on said cap and connected to said closure, 10 said member being adapted for use as a handle and to reciprocate said closure. 20
